TYPEWRITING MACHINE

Jesse A. B. Smith, Stamford, Conn., assignor to
Underwood Elliott Fisher Company, New York,
N. Y., a corporation of Delaware

Application December 27, 1939, Serial No. 311,106

7 Claims. (Cl. 197—136)

This invention relates to typewriting machines adapted especially for typing on cards such as licenses, index or file cards usually bearing a blank printed form for entry of data on the various typing lines thereof.

Typewriting machines adapted for writing on such form cards usually have the platen equipped with a card-holder by which insertion of the card into a machine is facilitated, and by which the bottom edge of the card is accurately located on the platen so that each successive card will assume the same position in relation to platen-rotation-limiting means provided to determine both the card-inserting and the first-line-typing positions of the platen. The first line-typing position determines the position of the other typing lines on the form in that, during typing, the card is advanced by the usual line-space mechanism. Such cards, although being substantially uniform in size and corresponding as to the printed form thereon, may have variations in the location of the form which occur in the printing of different batches of cards. Consequently the typing lines on a new batch of cards may be differently located from the bottom edge of the card and therefore be out of registry with the actual typing line positions as determined by the rotation-limiting means. The typing on the form would therefore be either above or below the actual form lines.

It is one of the objects of this invention to obviate the foregoing difficulties, and to accordingly provide simple and easily manipulatable means by which the rotative position of the card-locating device or card holder relative to the platen-rotation-limiting means may be adjusted to accommodate cards of different batches.

Another object is to provide improved platen rotation-limiting mechanism for determining both the card-inserting and first-line-typing positions of the platen, adapted for accurate and speedy adjustment to the first-line-writing position to any degree desired to compensate for varied or differently located forms on the cards.

A further object of the invention is to provide a typewriting machine of this character which, notwithstanding its adaptability, especially for the typing of printed form cards, may be easily and quickly converted for use as a conventional typewriter, and may again be quickly conditioned for form card typing at will.

Other objects and advantages will hereinafter appear.

In the drawing,

Figure 1 is a fragmentary perspective view of 53

the platen and carriage of a typewriter embodying the invention, portions of the mechanism being shown separated or broken away to facilitate illustration, and

5 Figure 2 is a fragmentary front elevational view of the mechanism embodying the invention, the clutch thereof being shown in section at a quarter turn from the position of Figure 1.

In the physical embodiment of the invention 10 illustrated, only such portions of the conventional typewriter as closely relate to the invention are shown, which include the usual platen 6 rotatably mounted by a shaft 7 on end members 8 and 9 of a platen carriage, and the usual line space mechanism of which a ratchet wheel 10 is shown, a spring-pressed detent 11 cooperating with the ratchet wheel to accurately position the platen 6 at each typing line.

To facilitate insertion of a form card into the 20 machine and to accurately locate the card on the platen 6, a card holding device 12 is provided, which may be substantially similar to that shown in patent to Lindburg 1,600,235. This type of card holder is preferred in that same is readily removable from the platen to condition the typewriter for conventional use. The card holder 12 comprises an elongate bar 13 disposed longitudinally on the platen and conforming to the periphery thereof, having at each end of the 25 platen a slotted plate 14 straddling the platen hubs and engaging flat faces thereof to retain the card holder non-rotatably on the platen, spring-pressed hook latches 15 being provided to removably secure the card holder in position. In 30 the present invention, the card holder 12 constitutes card-positioning means and serves to accurately position a form card 16 on the platen by receiving the lower portion of the card in an elongate recess 17 in the bar 13, which presents a shoulder 18 for abutment of the bottom edge 35 of the card therewith, all in the well-known manner.

Preferably at the end of the platen carriage, at which the line-space mechanism and its ratchet wheel 10 is disposed, the platen shaft 7, extending beyond the carriage end member 8, has a platen knob 19 fixed to the shaft, adjacent which the shaft carries a clutch 20. This clutch is 40 preferably of the friction type to provide adjustment to any degree desired, for the purposes herein-after made manifest.

In the organization of the clutch 20 illustrated, a disk 21 having a hub 22 secured to the platen shaft 7, constitutes the driving member of the clutch, this disk being rotated by manual opera- 50

tion of the platen knob 19 through the medium of the shaft 7. The driven member of the clutch is embodied in a clutch drum 23 which has a hub 24 rotatably journaled on the hub 22. The driving and driven members of the clutch, that is, the disk 21 and drum 23, are clutched and unclutched by the action of clutch shoes 25 which are movable to grip or release the clutch drum 23 and are pivotally held at corresponding ends to the disk 21, being thereby caused to rotate with the disk. The clutch shoes 25 are operated to grip or release the drum 23 by a slide cone 26 slideable on the shaft 7 and cooperating with a pair of clutch arms 27, each of which are flexibly connected to one of the shoes 25 by rollers 28, the arms 27 being fulcrumed together on a pin 29 seated in a groove of each arm. The clutch cone 26 is manually operable from a clutch knob 30 by slide rods 31 engaging the cone, as shown in Figure 1, the slide rods passing through the platen knob 19 and having the clutch knob 30 secured to their ends. With the clutch knob 30 pushed inwardly toward the platen, the clutch cone 26, cooperating with the arms 27, expands the clutch shoes 25, and the clutch drum 20 or driven member is thus clutched to the driving member or disk 21. Pulling knob 30 outwardly withdraws the clutch cone 26 from the arms 27 to contract the clutch shoes 25, thereby releasing the clutch drum 23. Although the structure and operation of the friction clutch herein shown has been specifically described, it will be understood that any suitable type of clutch may be employed in carrying out the invention.

The hub 24 of the clutch drum has the line-space ratchet wheel 10 secured thereto, and the clutch drum 23 has the stop plate 32 detachably mounted thereon, as by screws 33 shown in Figure 2. It will thus be noted that the ratchet wheel 10 and the stop plate 32 are each fixed on, and rotate with, the driven clutch member or drum 23. When the clutch 20 is connected, the ratchet wheel 10 and the stop plate 32 are fixed on the shaft 7 and therefore rotate in a constant relation with the platen 6. Release of the clutch 20 disconnects the ratchet wheel 10 and the stop plate 32 from the shaft 7 and the platen 6 may therefore be rotated independently of these elements by actuating the platen knob 19. The stop plate 32, cooperating with a normally fixed stop 34, limits rotation of the platen 6 to the angle indicated at X, that is, the angle included between stop shoulders 35 and 36 of the stop plate, less the thickness of stop 34. It may be here noted that the angular position of the stop plate 32 with respect to the line-space ratchet wheel 10 is to be such that engagement of the stop shoulder 36 with the stop 34 will arrest the platen exactly at a typing line as defined by the line-space detent 11 cooperating with the ratchet wheel 10.

To render the stop 34 ineffective, as required in converting the machine for conventional use, this stop is swingably mounted so as to be movable out of the path of the stop plate 32. Accordingly, the stop 34 takes the form of a lever having a finger piece at its end and pivoted at 37 on a bracket 38 secured to the carriage end member 8, the swing of the stop lever 34 being limited by a screw 39 thereon cooperating with a slot in the bracket 38.

The operation of the machine in the feeding and typing of form cards will now be described, with reference to Figure 1 wherein the card 16

is shown having a typical printed form thereon including blank lines upon which certain data is to be typed. In the normal use of the machine to type cards, the clutch 20 is set so that the ratchet wheel 10 and stop plate 32 rotate with the platen 6. Preparatory to inserting the card 16 into the machine, the platen is rotated to the position shown in Figure 1, defined by the stop shoulder 35 engaging the stop 34, the card holder 12 being thus brought to position at the front of the platen. The card 16 may then be easily placed with its bottom edge inserted into the recess 17 and against the shoulder 18. To begin typing, the platen is rotated backwardly from the card-inserting position until the shoulder 36 of the stop plate engages the stop 34. This brings the first typing line 40 on the card 16 in exact registry with the printing line Z of the machine, assuming that the angular position of the shoulder 18 of the card holder relative to the stop shoulder 36 has been previously properly adjusted.

In the conventional typewriter, the position of the typing line Z is indicated by the usual wing scale 41. The card holder 12, at card-inserting position forward of the platen, will be approximate the wing scale 41. It will be seen that the distance which the card 16 is to be moved from card-inserting to first-line typing position or vice versa, is represented by the dimension Y which is the actual distance of the first typing line 40 from the printing line Z. The distance X, which represents the extent of rotation of the platen, is therefore equivalent to the distance Y.

After typing the required data on the first typing line, each succeeding line is brought to typing position in the usual manner, as by operation of the line-space mechanism if the lines on the form card are spaced to agree with the regulator line spacing of the machine determined by the ratchet wheel 10 and detent 11. When the typing of the card is completed, the platen is further rotated in line-spacing direction until same is stopped at card inserting position as previously described, at which position the typed card is readily removed and a new card inserted. The typing of all of the form cards of a certain batch, on which cards the printing form is correspondingly located, is carried out in the same manner.

To compensate for the condition wherein the printed form on the card 16 is differently located from those previously typed, as in starting a new batch of cards, it is necessary to reset the platen to adjust the position of shoulder 18 thereon with respect to the stop plate 32 so that the first typing line 40 on the new card will accurately register at the printing line Z of the machine, this adjustment being done as follows: With the card 16 inserted into the card holder 12 and with the clutch 20 set, the platen 6 is rotated backwardly by turning the platen knob 19 until the shoulder 36 engages stop 34. The first typing line 40 of the card will thus be brought to approximate line typing position adjacent the printing line Z. The clutch 20 is then released and the platen 6 is thereby rendered free to be rotated independently of the limits effected by the plate 32 and independently of the line-space detent 11. It may be here noted that although the clutch 20 is released and the stop plate 32 is thereby disconnected from the shaft, the stop plate shoulder 36 is maintained against the stop 34 by the action of the line-space detent 11 on the

ratchet wheel 10. Following release of the clutch 20, the platen 6 is rotated by knob 19 to bring the first typing line 40 in exact registry with the printing line Z, after which the clutch 20 is again set. The machine is thus conditioned for typing on all of the cards having a correspondingly located printed form. After insertion of each succeeding card into the machine, the stop plate 32 will detain the platen to bring the card 16 accurately to first-line typing position by rotating the platen backwardly from card-inserting position. After completing the typing, further rotation of the platen in line-spacing direction will bring the card holder 12 in position to withdraw the typed card and insert a new card.

As aforeindicated, the machine constructed in accordance with the invention may be readily conditioned for conventional use by removing the card holder 12 and by swinging the stop lever 34 to ineffective position out of the path of the stop plate 32. By the withdrawal of the stop lever 34 to ineffective position, the stop plate 32 is rendered ineffective and the clutch 20 may therefore serve as a fractional line-space clutch in its conventional use to type above or below the typing lines determined by the line-space detent 11.

It will be seen from the foregoing that the invention provides improved platen rotation-limiting mechanism for determining both the card-inserting and first line typing positions of the platen, which mechanism is adapted for accurate and rapid adjustment to first-line printing position to compensate for varied or differently located forms on the printed cards. In the organization set forth, the friction clutch by which the adjustment is effected, affords adjustment to any degree desired. It will also be seen that the invention provides a typewriting machine which, notwithstanding its adaptability for typing of printed form cards, may be easily and quickly converted for use as a conventional typewriter.

What is claimed is:

1. In a typewriting machine having a rotatable platen with card-positioning means thereon, a shaft on which said platen is fixed, and a line-space mechanism including a ratchet wheel normally rotatable with the platen; a stop arranged to rotate with said ratchet wheel and adapted to cooperate with a second stop to limit the extent of platen rotation, and releasable means operatively connecting said ratchet wheel and said rotatable stop with said platen shaft to enable the relation of said card-positioning means with said ratchet wheel and said rotatable stop to be rotatively varied to any degree.

2. In a typewriting machine having a rotatable platen with card-positioning means thereon, a shaft on which said platen is fixed, and a line-space mechanism including a ratchet wheel normally rotatable with said shaft; a stop rotatable with said ratchet wheel and adapted to cooperate with a fixed stop to limit the extent of platen rotation, and a clutch operatively connecting said ratchet wheel and said rotatable stop with said shaft, said clutch being releasable to allow the relation of said card-positioning means with said ratchet wheel and said rotatable stop to be rotatively varied.

3. In a typewriting machine having a rotatable platen with removable card-positioning means thereon, and a line-space mechanism including a ratchet wheel normally rotatable with said platen; a stop rotatable with said ratchet wheel, a normally fixed stop adapted for engagement by said rotatable stop to limit the extent of platen rotation, and releasable means operatively connecting said ratchet wheel and said rotatable stop with said platen to enable the relation of said card-positioning means with said ratchet wheel and said rotatable stop to be rotatively varied, said normally fixed stop being movable to ineffective position out of the path of said rotatable stop.

4. In a typewriting machine having a rotatable platen having with removable card-positioning means thereon, a shaft on which said platen is fixed, and a line-space mechanism including a ratchet wheel normally rotatable with said platen; a stop rotatable with said ratchet wheel, a normally fixed stop adapted for engagement by said rotatable stop to limit the extent of rotation of said platen, and a friction clutch operatively connecting said ratchet wheel and said rotatable stop with said shaft, said clutch being releasable to allow the relation of said card-positioning means with said ratchet wheel and said rotatable stop to be rotatively varied, and means to disable one of said stops.

5. In a typewriting machine having a rotatable platen, and a line-space mechanism including a ratchet wheel normally rotatable with said platen; a stop rotatable with said ratchet wheel and adapted to cooperate with a counterstop to limit the extent of rotation of the platen in at least one rotative direction, and means including a normally engaged clutch operatively connecting said ratchet wheel and said rotatable stop with said platen, said clutch being releasable to allow said platen to be rotated independently of said ratchet wheel and said stop and to be connected therewith in varying positions.

6. In a typewriting machine having a rotatable platen and a line-space mechanism including a toothed wheel normally rotatable with the platen; a stop arranged to rotate in fixed relation with said toothed wheel and adapted to cooperate with a counterstop to limit the extent of rotation of the platen, and releasable means operatively connecting said toothed wheel and said rotatable stop with said platen to enable the relation of said platen with said toothed wheel and said rotatable stop to be rotatively varied to any degree.

7. In a typewriting machine having a rotatable platen with card-positioning means thereon and a line-space mechanism including a toothed wheel normally rotatable with the platen; a stop arranged to rotate in fixed relation with said toothed wheel and adapted to cooperate with a counterstop to limit the extent of platen rotation, and releasable means operatively connecting said toothed wheel and said stop with said platen to enable the relation of said card-positioning means with said toothed wheel and said stop to be rotatively varied to any degree.
